TELEPHONE SYSTEM

John H. Voss, Downers Grove, Ill., assignor to
 Associated Electric Laboratories, Inc., Chicago,
 Ill., a corporation of Delaware

Application November 19, 1934, Serial No. 753,603

5 Claims. (Cl. 179—39)

This invention relates in general to telephone systems but more particularly to substation instruments and circuits, and the main object briefly stated is the provision of an improved 5 substation instrument and circuits with which it is possible to communicate over either one of two lines connected thereto.

Telephone instruments of the above type have been provided with a number of push-buttons or 10 keys for performing the various switching operations, one of the keys being used for talking over one line, a second key for talking over another line, and a third key for establishing a holding circuit over a particular one of said lines. In 15 some instances all of the operated keys were restored in response to the replacement of the receiver or the keys were all manually restored in case no automatic restoring arrangement was provided. In addition, in other instances the operation of a second key automatically restored the first actuated key and in other cases the line connecting key, where a single key controls the connection of more than one line to the substation circuit, is locked against operation until 20 the receiver is removed thereby temporarily connecting the substation circuit to one of the lines at the instant the receiver is removed when a connection with the other line is desired.

It is the object of the invention to provide a 25 telephone instrument and circuits such that a single line connecting key is operable independent of the switchhook to connect either one of two lines to the substation circuit and two holding keys, which close holding circuits for the two 30 lines, are only operable at will when the receiver is removed and which holding keys are automatically restored upon the replacement of the receiver. This arrangement overcomes a number of objections found in the previously mentioned types.

A feature of the invention relates to an improved holding circuit for both lines, each line having a holding bridge including the impedance of only one of the ringer coils of such lines.

Other objects and features of the invention will be apparent from the following description.

In the drawing Fig. 1 shows the schematic circuits for connecting two lines to a single substation circuit; Fig. 2 is a side view of one of the lever type keys and the switchhook controlled operating member; and Fig. 3 shows a partial rear view of the keys and spring actuating mechanism.

The substation instrument comprises a well-known cradle-type telephone set having a sub-

base for mounting the key levers and associated mechanism. S indicates the circuit of the cradle-type substation circuit, while the dotted line SB indicates the sub-base containing the switching mechanism diagrammatically represented therein. Two lines, line #1 and line #2, shown to the right in Fig. 1 may be two local lines, a local line and a trunk line, or two trunk lines extending to an automatic telephone exchange.

The mechanism in this application is substantially the same as the mechanism shown and described in Obergfell Patent #1,956,360, issued April 24, 1934, except for some changes which are shown in Figs. 2 and 3.

These mechanism changes permit the line connecting key 10 to be manually operated at any time regardless of the position occupied by the switchhook operating member and is not operated by the replacement of the receiver on the cradle. The holding keys 20 and 30 are locked 10 against manual operation when the receiver is resting on its cradle while after the receiver is removed both keys can be operated at will to open and close the holding circuits controlled 15 thereby. In addition the replacement of the receiver on the cradle restores either or both holding 20 keys.

Referring now to Figs. 2 and 3, key levers 10, 20, and 30 extend through an opening in the sub-base SB. The key levers 10, 20, and 30 are pivoted on shaft 11 journaled in extension plates secured to the sub-base. A space bushing is provided on shaft 11 between each of the keys 10, 20, and 30. The other end of the key levers are connected by pins 31, 21, and 12 to the link members 32, 22, and 13, respectively. The end of the link members 32, 22, and 13 are fork-shaped so that they move in and out on pins, such as pin 35, passed through the U-shaped portions of members 33, 41, and 15 which serve as supports 30 for insulated bushings, such as bushings 36 and 16. The members 33, 41, and 15 are rotatable on a rod 34. As more clearly shown in Fig. 2, it 35 will be seen that when the key lever 30 is moved downward and rotated on shaft 11 it imparts movement to the link 32 by means of pin 31. Link 32 engages pin 35 in member 33 forcing member 33 to the right so that bushing 36 will engage and close springs 80. In a similar manner links 22 and 13 rotate members 41 and 15 to cause the associated bushings to operate springs 81, 82 and 83. Each of the key levers operates on a toggle principle, for instance, when key 30 is operated downward the pin 31 connecting the 40 end of the key and link 32 assumes a position 45

beyond a center line drawn between shafts 11 and 35 to hold the key in its operated position. Stop rod 66 serves as a stop for the normal position of the keys. The rod 65 serves as a stop 5 for hold keys 30 and 20 in their operated positions while a bracket 40 mounted on plate 8 serves as a stop for line connecting key 10 in operated position.

Hold key levers 20 and 30 may only be operated 10 when the receiver is off the cradle or switchhook and are automatically restored to normal position in response to the replacement of the receiver on the cradle. Referring to Fig. 2, rod 50 which is controlled by the receiver, is shown in position 15 indicating that the receiver is resting on the cradle. Rod 50 bears on insulating washer 51 which is attached to the movable lever arm 52. Arm 52 is pivoted so that it is rotatable about the pin 53. A pair of flat shaped lever arms 56 are 20 secured together by means of pins 63, 61, and 55. At the rear of the key unit the pin 55 is engaged by hook 54 formed in lever 52. A link member 60 is pivoted by pin 61 to the lever 56 and the opposite end is securely pivoted to the bearing pin 25 62 which is journalled in the extension plates of the sub-base. The end of link 60 is provided with a rod 71 provided with bushings 70 and 72 for operating springs, such as springs 75, 78, and 79. When lever 52 is moved downward it moves lever 30 56 upward by hook 54 engaging pin 55. This imparts a rotary motion to link 60 because it is pivoted at 62 and causes the plates 56 to be thrust forward or to the left as shown in Fig. 2. The rotation of link member 60 causes the bushings 35 70 and 72 to open springs 78 and 79.

The left end of plates 56 are held together by pin 63 in the release arm 64. The arm 64 is rotatable about shaft 34 so that the forward movement of levers 56 will pivot arm 64 about shaft 40 34 and pin 63 to cause the releasing rod 65, secured to arm 64, to press upon the top side of the link members 32 and 22. This downward motion of rod 65 restores keys 20 and 30 to their 45 normal positions against stops 66. The rod 65 does not extend over to member 13 of key 10 and therefore the rod 65 does not restore key 10 as shown in the above mentioned Obergfell patent.

When the receiver or handset is removed from the cradle rod 50 moves upward and the levers 50 56 move to the right, as seen in Fig. 2, due to the spring tension of springs 75 which bear against bushings 70 and 72. This movement closes springs 78 and 79. Arm 56 in moving to the right raises the rod 65 so as to permit operation of 55 keys 20 and 30. It will be noted that springs 80 and 81 are non-locking and therefore with the receiver off the switchhook the holding circuits may be opened and closed at will. Further detailed description of the key mechanism and operation may be had by referring to the above-mentioned Obergfell patent.

Fig. 1 shows by means of the usual circuit diagrams a substation circuit S comprising a calling device CD, transmitter T, receiver R, induction 65 coil IC, and the cradle springs CS shown in operated position with the handset removed from the cradle. The dotted line illustrates the sub-base SB mounting the push-button PB, line connecting key 10, hold keys 20 and 30 and associated 70 springs which the keys control. The ringer bell RB1 for line 1 and the ringer bell RB2 for line 2 are mounted in separate ringer-boxes terminating the two lines.

With the keys in normal position the substation 75 circuit is normally connected to line 1 and

therefore the subscriber need not operate any keys to originate or answer a call on line 1. Key 10 may be operated either before or after the handset is removed from the cradle, thus making it possible for the subscriber to select the desired 5 line before removing the handset. Assuming now that all the keys are in normal position then when the subscriber answers or originates a call by removing the handset the cradle springs CS close to connect the substation circuit S to line 1 10 as follows: from line 1 by way of conductors 90 and 92, normally closed springs controlled by springs 82 and 83 and thence by way of the heavy talking conductors and push button PB and cradle springs CS. Springs 78 and 79 in the sub-base SB close in response to the removal of the handset to prepare points in the holding circuits for lines 1 and 2. Assuming now that the subscriber receives a call over line 2 while conversing over line 1, such subscriber, after telling the 20 party on line 1 to hold the connection, will operate hold key 30 thereby operating member 33 and bushing 36 to close springs 80 thereby completing a holding circuit for line 1 as follows: from conductor 90 of line 1, the upper ringer coil of RB1, 25 conductor 91, springs 79 and 80 to line conductor 92. The subscriber now operates the key 10 to its operated position to operate member 15 and bushings 16 to operate springs 83 and 82 to disconnect line 1 from the substation circuit and 30 connect line 2 thereto. The substation S is now connected to line conductors 93 and 95 by way of the make contacts and springs 82 and 83. If desired the subscriber may hold this connection by operating hold key 20 thereby closing springs 35 81 to complete a holding circuit for line 2 as follows: from conductor 93, upper ringer coil of RB2, conductor 94, springs 78 and 81 to conductor 95. In case conversation is terminated over line 2 the subscriber need not operate the hold 40 key 20 or push button PB to release the connection on line 2 but operates the line connecting key 10 to disconnect from line 2 and return to line 1. The impedance of the ringer coil in the holding bridge of line 1 is sufficiently high so 45 that the subscriber can talk on the line even though the holding circuit is closed. However, it is not necessary to talk with the holding bridge on the line because the subscriber can remove the holding bridge by restoring key 30. After conversation the subscriber need not restore any of the operated keys since the hold keys 20 and 30 are automatically restored, if operated, in response to the replacement of the receiver and the forward thrust of arms 56 for operating rod 55 65 as previously described. The line connecting key 10 however remains in the position last operated by the subscriber since the replacement of the receiver does not in any way control its operation. The substation circuit may therefore 60 be left connected to either line as desired dependent upon the position of the line connecting key 10, the hold keys may be operated at will only when the receiver is removed from the cradle to open and close the holding circuits, and such 65 hold keys and holding circuits being automatically restored and opened in response to the replacement of the receiver.

Having described the invention, what is considered to be new and is desired to have protected by Letters Patent will be set forth in the following claims.

What is claimed is:

1. In a telephone system, a substation, a first and a second line terminating in said substation, 75

a holding circuit for each of said lines in said substation, holding means individual to each line for closing and opening said holding circuits, a supporting member in said substation, a receiver in said substation adapted to rest on said supporting member when not in use, means for rendering said holding means effective for manual operation to open or close said holding circuits responsive to the receiver being removed from the supporting member, said last means restoring any operated holding means to open the corresponding holding circuit and for disabling said holding means against manual operation responsive to the receiver being replaced on said supporting member.

2. In a telephone system, a substation, a first and a second line terminating in said substation, a holding circuit for each of said lines in said substation, holding means individual to each line for closing and opening said holding circuits, a supporting member in said substation, a receiver in said substation adapted to rest on said supporting member when not in use, means for rendering said holding means effective for manual operation to open or close said holding circuits responsive to the receiver being removed from the supporting member, said last means restoring any operated holding means to open the corresponding holding circuits and for disabling said holding means against manual operation responsive to the receiver being replaced on said supporting member, a substation circuit in said substation, and line connecting means in said substation manually operable at will regardless of the position of said receiver and supporting member for connecting said substation circuit to either one of said lines.

3. In a telephone system, a substation, a first and a second line terminating in said substation, a holding circuit for each of said lines in said substation, holding means in said substation individual to each line and manually operable after removal of the substation receiver from the switchhook for completing or opening its individual holding circuit, and switchhook controlled means for preventing the operation of said holding means while the receiver is on the switchhook and for automatically restoring any operated holding means to open its individual holding circuit in response to the replacement of the receiver on the switchhook.

4. In a telephone system, a substation, a first

and a second line terminating in said substation, a holding circuit for each of said lines in said substation, holding means in said substation individual to each line and manually operable after removal of the substation receiver from the switchhook for completing or opening its individual holding circuit, switchhook controlled means for preventing the operation of said holding means while the receiver is on the switchhook and for automatically restoring any operated holding means to open its individual holding circuit in response to the replacement of the receiver on the switchhook, and line connecting means in said substation operable independently of said switchhook controlled means for connecting either one of said lines to the talking circuit of said substation.

5. In a telephone system, a plurality of sets of springs, a substation circuit and a first and a second line terminating in said sets, a line connecting key for operating the first set of said springs to connect either one of said lines to said substation circuit dependent upon the operated position of said line connecting key, a first holding key for operating the second set of springs, a holding circuit for said first line including said second set of springs, a second holding key for operating the third set of springs, a holding circuit for said second line including said third set of springs, an operating member having a plurality of positions, means controlled by said operating member in its first position for preventing the operating of said holding keys and the operation of their spring sets, said means controlled by said operating member in its second position for permitting manual operation of said holding keys and the operation of said corresponding spring sets to open and close said holding circuits at will, said line connecting key manually operable at any time regardless of the occupied position of said operating member to operate its corresponding spring set and connect either of said lines to said substation circuit, means for operating said operating member from its second position to its first position, said first means operated responsive thereto for restoring only said holding keys and their corresponding spring sets to open the holding circuits without restoring the line connecting key and its corresponding spring set.
